UNITED STATES PATENT OFFICE.

GOTTFRIED ISLIKER-BRAUEN, OF BRUGGEN, ST. GALLEN, SWITZERLAND.

BOOKBINDING MACHINE.

Application filed May 11, 1922. Serial No. 560,074.

To all whom it may concern:

Be it known that I, GOTTFRIED ISLIKER-BRAUEN, a Swiss citizen, and residing at Bruggen, St. Gallen, Switzerland, have invented certain new and useful Improvements in Bookbinding Machines, of which the following is a specification.

My invention has reference to improvements in book binding machines and relates more particularly to a device for operating on the folded and stitched signatures for the purpose of twisting together the loose thread ends protruding in alined rows from the folds of the gathered signatures. The device is especially suitable in the binding of brochures, pamphlets and the like, which at present generally are handled in a stitching attachment of the folding machine. The loose ends of the individual stitches in the prior art are simply glued to the back of the booklet and are then very apt to work loose again causing the respective signatures to become unfastened.

The object of the present invention is to improve this rather primitive fastening method by twisting the protruding thread ends of the alined signature stitchings about one another into rope-like formation just prior to gluing, which then effectively prevents them from becoming undone. Furthermore, by operating on the two ends of each stitch in opposite sense, the stitches are drawn taut again just prior to being glued down, which makes for a very tight binding. The work done on this relatively simple stitch twisting machine is practically equal to that of a high-priced complicated stitching machine.

My invention will best be understood when described in connection with the accompanying drawings, in which Fig. 1 is a side elevation, partly in section, of the new twisting machine with a series of booklets set up on the work table; Fig. 1^a illustrates the left end of the work table with its supporting upright; Fig. 2 is an end elevation, partly in section, of the machine with the work feeding unit removed; Fig. 3 is a side view, partly in section, of the twisting mechanism proper, of which Fig. 4 is a fragmentary plan view; Fig. 5 shows a lever mechanism for controlling the work feed; Figs. 6, 7 and 8 are side views of variously shaped twisting tool heads; Fig. 9 shows the back of a plurality of folded and stitched signatures, with the thread

ends in each row twisted about each other and a stiffening thread which is fed forward through the hollow twisting tools; Fig. 10 shows the twisted rope formation on a larger scale; Fig. 11 is a fragmental vertical section through the twisting mechanism proper, showing one book finished, the second just being glued, and the third about to be operated on by the twisting tool.

Standards 1, 21 and 32 support the several machine parts. The work table 20 with its adjustable lateral cheeks 24, is carried by the upright 21 (Fig. 1^a) and the short support 4. The twisting unit proper is supported by lateral carrier members 2 and 3, and the work feeding unit is supported on the base 31 above the standard 32. The supports 2 and 3 respectively carry plates 5 and 5' (Fig. 2) each provided with two identical slots 6 (Figs. 3 and 4). The number of plates 5 (5') depends upon the size of the machine and the number of rows of stitchings effected by the preceding stitching operation. As shown, by way of example, two such slotted plates 5 are used, which makes the machine adapted for use in connection with a two-row stitching machine, as shown in Fig. 9. For each such slot 6 there is provided a twisting instrumentality, each comprising a spindle 7 (7', 7'', 7''') to the lower end of which a toothed wheel 12 (12', 12'', 12''') is secured (Fig. 2) and to the upper end a collar 10 (Figs. 3 and 11). The wheels 12 and 12', and 12'' and 12''' respectively are in mesh. To the wheels 12 and 12'' are secured pulleys 120 (Fig. 3). In the support brackets 13 and 13', respectively extending from the supports 2 and 3, are mounted the shaft 14 with pulleys 16 and the rod 15 which serves as thread guide and is provided with guide perforations 115 (Fig. 4). Blocks of wood 55 covered with a layer of felt or similar material 56 are arranged in the slots 7 and serve to comb or brush back the thread ends, protruding from the superimposed book backs, in the direction of the arrow in Fig. 11.

The twisting members, which are preferably in the form of hollow tubes, are journaled in ball bearings 8 and 9 and can be rapidly rotated in suitable manner, for instance by a rope drive acting on the pulleys 120 of the meshing wheel pairs. In the machine frame is rotatably journaled the shaft 17 which is driven over the pulley 19

and to which are fixed the pulleys 18, 33 and 34. An endless rope 58 runs over the pulley 18, the pulleys 16 on shaft 14, and over the pulleys 120, causing the several 5 twisting tools to rotate rapidly with uniform speed, but with the two tools of each connected pair running in opposite directions.

The upper ends of the twisting tubes are 10 shaped to engage in their rotation the loosely depending thread ends for twisting them together. The tube end 112 (Fig. 8) shows hook-shaped prongs 113; the tube end 112' in Fig. 6 presents pointed teeth 113', and in 15 Fig. 7 a wire spiral 111 is placed partways over the tube end, and it is this latter arrangement which is shown in operative position in Figs. 3, 4 and 11, as specially suitable for the intended purposes.

20 On a machine bracket 22 are mounted bobbins 23, 23', 23'' and 23''', whose respective threads 60, 60', 60'' and 60''' are passed through the guide bores 115 in shaft 15 and then up through the hollow twisting 25 tubes with their front ends drawn out to a length of about 1 inch on the plate 28 forming part of the work table and sunk a little below the table level. Between the supports 2 and 3 are rotatably mounted in 30 brackets 25 and 25' (Fig. 4) the glue roller pairs 62, 62' and 26, 26', the latter preferably circumferentially recessed to receive the smaller glue applying rollers 62 and 62' respectively. The larger rollers dip below 35 into the glue receptacle 29, suitably heated, for instance by an electric heating device W. The gluing rollers 62 and 62' extend through corresponding slots in the plate 28 (Fig. 11) to nearly the level of the work 40 table surface.

The work feeding unit comprises the base 31 supporting bearings 35 and 35' in which is horizontally mounted the inwardly threaded sleeve 36 in which is longitudinally 45 displaceable the screw spindle 37. On the sleeve is rotatably mounted a small pulley 43 with a clutch half 44 for the backward feed of the screw spindle, and the larger pulley 42 with a clutch half 45 for its forward feed. A clutch member 46, axially displaceable on the sleeve 36, but secured thereon against relative rotary displacement by means of a key and feather arrangement 54, can be alternately coupled with the clutch halves 44 and 45. The pulley 43 is driven from the main shaft pulley 33 and the pulley 42 from pulley 34. On the front end of the screw spindle 37 is mounted the pusher plate 38 from which extends rearwardly the rod 39 on which are adjustably mounted the stop collars 40 and 41.

A forked lever 48, pivoted at 49 to a fixed machine part, is connected on the one hand to the clutch member 46 by the trunnions 65 47 and 47', and on the other hand by the

fitting 53 to the rod 39. For securing the forked lever 48 temporarily in the respective end positions there is provided a lever 50, fulcrumed at 51 and cooperating with the upper end of the lever 48 by the interposed roller 52. A draw-spring 50' tends to keep the roller in operative contact with the lever end.

The operation of the described mechanisms is the following: The folded and 75 stitched signatures forming the units are set up on the feed table with always a spacing member 63 between each two units, the rear-most unit in close contact with the pusher plate 38 and the first unit just back of the 80 felt covered plates 56 in the slots 6. The feeding mechanism is then started by moving the lower end of the forked lever 48 towards I (Fig. 5) which causes the clutch member 46 to couple-in the pulley 42. This 85 causes forward feed (arrow in Fig. 1) of the spindle 37 with the attached pusher plate 38, whereby the row of booklets is moved forward, the units passing first over the felt plates 26, whereby the loose thread ends depending from the signature folds are brushed back against one another (Fig. 11). During the further advance of each unit the twisting tools, the spirals 111, seize the 90 thread ends and twist them about one another and at the same time about the stiffening thread 60 issuing through the twisting tubes. The result is a tight twist, and as, in the constructional arrangement illustrated, the meshing wheels of each twisting 95 unit revolve in opposite directions, the one tool operating on the one end and the other tool on the other end of the stitch threads, the stitches will be additionally drawn taut 100 thereby.

The twisted unit is steadily fed forward and passes over the gluing device where the twists are glued by coming in contact with the glue applying rollers 62 and 62'. The unit having been pushed beyond the 110 gluing device, the stiffening threads 60, 60', 60'' and 60''' are severed and the ends of the stiffening threads issuing from the twisting tubes are drawn out again the required length to be laid out on the plate 28 for the 115 ensuing twisting operation.

In Fig. 9 is shown diagrammatically the back of a booklet having been stitched with two rows of stitches the rows *a* and *b*, and the rows *c* and *d* marking the ends of the 120 respective stitches.

Obviously, only one row of stitches or more than two, as shown, may be used, in which instances only two or more than 4 thread twisting units must be provided; and it is also possible to obtain a satisfactory 125 result by dispensing with the stiffening thread fed through the hollow twisting tool, if a simple and cheaper machine is wanted.

As soon as the last unit 61 has arrived in 130

position 61' (Fig. 11) the collar 41 contacts with the fitting 53, when the forked lever 48 will be laid over toward II (as shown in dotted outline in Fig. 5). This uncouples the forward drive and couples the clutch member 46 with the clutch half 44 which throws in the return drive of the screw spindle to quickly return the latter into the initial position of Fig. 1. The collar 40 is so adjusted that on its contact with the fitting 53 the forked lever 48 will be actuated just enough to move the coupling member 46 into the neutral position, when the spindle will remain at rest. A new series of booklets is then set up on the work table and the operation started over again.

What I claim is:—

1. In a machine for twisting together the thread ends depending from the folds of stitched signatures, a twisting instrumentality for each row of alined thread ends, comprising a revolubly journaled twisting spindle presenting a thread seizing head, and means for rotating said twisting spindles in unison.

2. In a machine for twisting together the thread ends depending from the folds of stitched signatures, a twisting instrumentality for each row of alined thread ends, comprising a revolubly journaled axially perforated twisting tool presenting a thread seizing head, and means for rotating said twisting tools.

3. In a machine for twisting together the thread ends depending from the folds of stitched signatures, a twisting instrumentality for each row of alined thread ends, comprising a rotary twisting spindle and a wire spiral axially extending therefrom and designed for seizing the thread and twisting them together in the sense of the spiral convolutions.

4. In a machine for twisting together the thread ends depending from the folds of stitched signatures, a twisting instrumentality for each row of alined thread ends, comprising an axially perforated rotatable twisting spindle and for each such spindle

means for feeding a stiffening thread axially therethrough to be intertwined with the 50 stitch thread ends.

5. In a machine for twisting together the thread ends depending from the folds of stitched signatures, a twisting unit for each row of stitch thread ends, each unit comprising two rotatable twisting tools, one of which operates on the one row of depending thread ends and the other one of which operates on the other row of depending thread ends in the same row of stitches, and means for rotating the two twisting tools in each unit in relative opposite directions.

6. In a machine of the character set forth, in combination with a work table presenting slots, in each slot a rotatable twisting tool 65 and thread brushing means ahead of each twisting tool to properly present the thread ends to the twisting tools.

7. In a machine for twisting and gluing together the thread ends depending from the folds of stitched signatures, in combination, a machine frame including a work table presenting slots and a main drive, a twisting instrumentality in each table slot adapted to seize the depending stitch thread ends 75 and twist them together, means in advance of said twisting instrumentalities for properly presenting the depending thread ends to said twisting instrumentalities, means for intertwisting with said stitch thread ends a 80 stiffening thread, a gluing device for gluing the individual twisted thread formations, and a work feed mechanism including a pusher plate, for advancing the work on said table and for returning said pusher plate into 85 the initial position at a predetermined period and for then automatically arresting the machine operation, said twisting instrumentalities and said work feed mechanism all being operated by said main drive. 90

In testimony whereof I have affixed my signature in presence of two witnesses.

GOTTFRIED ISLIKER-BRAUEN.
